UNITED STATES PATENT OFFICE.

WILMONT BILLS, OF DOWAGIAC, MICHIGAN, ASSIGNOR TO DOWAGIAC MANUFACTURING COMPANY, OF DOWAGIAC, MICHIGAN.

DISK FURROW-OPENER.

SPECIFICATION forming part of Letters Patent No. 744,711, dated November 24, 1903.

Application filed March 28, 1903. Serial No. 150,074. (No model.)

To all whom it may concern:

Be it known that I, WILMONT BILLS, a citizen of the United States, residing at the city of Dowagiac, in the county of Cass and State 5 of Michigan, have invented certain new and useful Improvements in Disk Furrow-Openers, of which the following is a specification.

This invention relates to improvements in 10 disk furrow-openers. It is particularly adapted for use in grain-drills, although desirable for use in other relations.

The objects of the invention are to provide 15 an improved disk furrow-opener in which the disks are satisfactorily cleaned and the collection of soil and trash prevented.

A further object is to provide an improved 20 scraper mechanism for disk furrow-openers in which the tension can be quickly and easily adjusted.

Further objects will definitely appear in 25 the detailed description to follow.

I accomplish the objects of my invention 30 by the devices and means described in the following specification.

The invention is clearly defined and pointed out in the claims.

A structure embodying the features of my 35 invention is fully illustrated in the accompanying drawings, forming a part of this specification, in which—

Figure 1 is a detail side elevation view of a 40 double-disk furrow-opener embodying the features of my invention, portions being broken away to show the arrangement of the parts. Fig. 2 is a detail sectional view taken on line 45 2 2 of Fig. 1. Fig. 3 is an enlarged detail sectional view taken on lines 3 3 of Figs. 1 and 4. Fig. 4 is a detail view taken on line 4 4 of Fig. 5. Fig. 5 is a detail sectional view taken on line 5 5 of Fig. 1. Fig. 6 is a detail plan view showing the spring-pressure connection for the scraper-blades F for the inner faces of the disk, and Fig. 7 is a plan view of one of 50 the scraper-blades F.

In the drawings the sectional views are taken looking in the direction of the little arrows at the ends of the section-lines, and similar letters of reference refer to similar 55 parts throughout the several views.

Referring to the lettered parts of the draw-

ings, the boot A is of the usual or any desired form. The bearings for the disks B B, also of any desired form, are carried by the boot.

Projecting forwardly from the boot A is a 55 bracket A'', to which the draw-bar A''' is secured. On each side of the bracket A'' are projecting lugs a, which are provided with suitable bearings to receive the journals of the brackets C, by which the scraper-blades 60 are supported. The scrapers D are adapted to rest against the outer faces of the disks. Pressure is applied to these scraper-blades by blade-springs C' C', which are secured at one end to the brackets C and are adjustably 65 secured together at the opposite end by a link E, into which the bolts e, which are passed through the ends of the springs, are threaded. The bracket A'' is provided with a suitable perforation or opening E', through which 70 the link E extends, so that the tension upon the scrapers D is capable of complete and easy adjustment and the tension on the two blades is equal at all times.

The blades D are pivotally secured to the 75 brackets C by heads d', which are journaled upon the pivot c of the bracket C. These heads d' are preferably formed of malleable iron with extending lugs at each side, so that the scraper-blade may be placed in position 80 and the lugs hammered down upon the same, as clearly appears in Figs. 1 and 4. They are also provided with a lug f, which is adapted to engage the flange c' to retain the head upon the pivot. By this structure the 85 parts may be produced very economically and they are conveniently and economically assembled, and should the blades D become worn new ones may be readily inserted. By this arrangement of parts the blades are 90 held against the disks by a yielding pressure and are perfectly free to yield to any obstruction, so that wear upon the same is reduced to a minimum and also the danger of breaking the supports. 95

The inner faces of the disks B are freed from soil, and the accumulation of trash is prevented by scraper-blades F, which project between the same to the rear of the boot. (See Figs. 1 and 5.) These scraper-blades F are 100 supported upon a bracket A', which extends rearwardly from the boot and are held against

the inner faces of the disks by spring-pressure. The scraper-blades F are slotted at n' to engage the pin g' on the bracket A and are pivotally secured together at their inner lower ends 5 by a suitable rivet or the like g. A spring h, which is retained in position by a pin h', engages suitable perforations in the upper ends of the blades F, so that they are held outwardly against the inner faces of the disks.

- The spring h is formed in one place so that the scraper-blades F are held against the disk with an equal pressure. Several perforations n are provided in the upper edges of the blades to engage the spring h, so that the 15 tension can be adjusted or the blades can be adjusted to compensate for wear. This scraper is also very easy to construct and quickly assembled. In assembling, the ends of the spring h are engaged in perforations in
- 20 the upper ends of the blades, and the blades are swung down between the disks onto the pin g' and there retained by a suitable cotter-pin or the like. By this arrangement of parts the pressure is applied to the scraper-blades in a simple and satisfactory manner.
- 25 A structure is produced which is economical and durable.

I have illustrated and described my invention in the form preferred by me on account 30 of its simplicity and economy in manufacture and durability in use. I am aware, however, that it is capable of very considerable variations in structural details without departing from my invention.

35 Having thus described my invention, what I claim as new, and desire to secure by Letters Patent, is—

1. The combination of a boot A; a bracket A" projecting to the front thereof; furrow-opening disks B; brackets C pivotally supported to each side of said bracket A"; scraper-blades D adapted to rest against the outer faces of said disks; heads d' to which said scraper-blades D are secured, pivotally 40 supported on said brackets C; springs C' secured at one end to said brackets C; a loop E extending through a suitable perforation in said bracket A"; screw-threaded bolts through said springs C' adapted to engage said 45 loop E; a bracket A' projecting to the rear of said boot; a pair of scraper-blades F pivotally secured together at their inner ends arranged between said disks; transverse slots in said blades F; a pin g' on said bracket A' adapted to engage said slots; perforations n in the upper end of said scraper-blades; and a spring h adapted to engage said perforations, all coacting for the purpose specified.

2. The combination of a boot A; a bracket A" projecting to the front thereof; furrow-opening disks B; brackets C pivotally supported to each side of said bracket A"; scraper-blades D adapted to rest against the outer faces of said disks supported on said 55 brackets C; springs C' secured at one end to said brackets C; a loop E extending through a suitable perforation in said bracket A";

screw-threaded bolts through said springs C' adapted to engage said loop E; a bracket A' projecting to the rear of said boot; a pair of 70 scraper-blades F pivotally secured together at their inner ends arranged between said disks; transverse slots in said blades F; a pin g' on said bracket A' adapted to engage said slots; perforations n in the upper end of said 75 scraper-blades; and a spring h adapted to engage said perforations, all coacting for the purpose specified.

3. The combination of a frame; furrow-opening disks; brackets C pivotally supported 80 on said frame; scraper-blades D adapted to rest against the outer faces of said disks pivotally supported on said brackets C; springs C' secured at one end to said brackets C; an adjustable connection for the opposite ends 85 of said springs; a pair of scraper-blades F pivotally secured together at their inner ends arranged between said disks; transverse slots in said blades F; a pin on said frame adapted to engage said slots; and a spring h supported 90 on said frame adapted to engage said blades F, all coacting for the purpose specified.

4. The combination of a frame; furrow-opening disks; brackets C pivotally supported 95 on said frame; scraper-blades D adapted to rest against the outer faces of said disks supported on said brackets C; springs C' secured at one end to said brackets C; an adjustable connection for the opposite ends of said 100 springs; a pair of scraper-blades F pivotally secured together at their inner ends arranged between said disks; transverse slots in said blades F; a pin on said frame adapted to engage said slots; and a spring h supported 105 on said frame adapted to engage said blades F, all coacting for the purpose specified.

5. The combination of a frame; furrow-opening disks; pivotally-supported scraper-blades adapted to rest against the outer faces 110 of said disks; springs for applying pressure to said blades; an adjustable connection for the free ends of said springs; a pair of scraper-blades arranged between said disks; a suitable support therefor; and means for applying 115 pressure to said blades, for the purpose specified.

6. The combination of a frame; furrow-opening disks; pivotally-supported scraper-blades adapted to rest against the outer faces 120 of said disks; springs for applying pressure to said blades; a connection for the free ends of said springs; a pair of scraper-blades arranged between said disks; a suitable support therefor; and means for applying pressure 125 to said blades, for the purpose specified.

7. The combination of a boot A; a bracket A" projecting to the front thereof; furrow-opening disks B; brackets C pivotally supported to each side of said bracket A"; 130 scraper-blades D adapted to rest against the outer faces of said disks; heads d' to which said scraper-blades are secured, pivotally supported on said brackets C; springs C' se-

cured at one end to said brackets C; a loop E extending through a suitable perforation in said bracket A"; screw-threaded bolts through said springs C' adapted to engage said loop E, for the purpose specified.

8. The combination of a boot A; a bracket A" projecting to the front thereof; furrow-opening disks B; brackets pivotally supported to each side of said bracket A"; scraper-blades D adapted to rest against the outer faces of said disks supported on said brackets C; springs C' secured at one end to said brackets C; a loop E extending through a suitable perforation in said bracket A"; screw-threaded bolts through said springs C' adapted to engage said loop E, for the purpose specified.

9. The combination of a frame; furrow-opening disks; brackets pivotally supported to each side of said frame; scraper-blades adapted to rest against the outer faces of said disks pivotally supported on said brackets; springs secured at one end to said brackets; and a connection for the free ends of said springs, for the purpose specified.

10. The combination of a frame; furrow-opening disks; brackets pivotally supported to each side of said frame; scraper-blades adapted to rest against the outer faces of said

disks supported on said brackets; springs secured at one end to said brackets; and an adjustable connection for the free ends of said springs, for the purpose specified.

11. The combination of a frame; furrow-opening disks; a pair of scraper-blades F pivotally secured together at their lower ends arranged between said disks; transverse slots in said blades; a pin on said frame adapted to engage said slots; perforations in the upper end of said scraper-blades and a spring h supported on said frame, adapted to engage said perforations, for the purpose specified.

12. The combination of a frame; furrow-opening disks; a pair of scraper-blades having transverse slots therein pivotally secured together at their inner ends arranged between said disks; a pin on said frame adapted to engage said slots; and a spring adapted to hold said blades normally outward, for the purpose specified.

In witness whereof I have hereunto set my hand and seal in the presence of two witnesses.
